DEVICE FOR EFFECTING CONTROLLED VARIATIONS OF GEOMETRICAL FORMS AND OTHER SHAPES

Stanley William Charles Andrews and James Henry Dwyer, Mitcham Junction, England, assignors to Precision Grinding Limited, Mitcham Junction, England

Application September 10, 1951, Serial No. 245,942

Claims priority, application Great Britain
September 15, 1950

3 Claims. (Cl. 33—23)

This invention relates to a device for controlled variation of geometrical forms and other shapes and capable of being used either independently or as a controlling attachment in conjunction with a pantographic copying machine.

Pantographic copying machines are known which transfer delineations from an image or matrix on to the work-piece by means of a lever system which ensures a true reproduction of the master design at a given reduced or increased ratio in two or three dimensions.

The device according to the present invention is intended to be inserted between the matrix or the like and the tool and is adapted to impart to the latter, by the provision of appropriate attachments, either directly or through the pantograph of the copying machine, movements which will effect any of the following results:

1. Convert a vertical line into one inclined at any desired angle. As examples of practical application of such a conversion may be mentioned: production of an italic letter from an upright or vertical one, a parallelogram from a square, or an inclined ellipse from a true circle.

2. Lengthen or shorten designs horizontally. As examples of practical applications may be mentioned: conversion of a square into a rectangle or a true circle into an ellipse.

3. Reproductions in three dimensions of the conversions referred to above under 1 and 2.

The invention consists in a copying device capable of effecting controlled variations of geometrical forms and other shapes comprising: a base to which the image or matrix to be reproduced is secured; a first carriage slidably mounted along the base; a stylus carrying second carriage mounted on and moving with the said first carriage and being capable of sliding transversely to it in a direction across the base; a top slide mounted on and moving with the stylus carrying second carriage, being capable of sliding thereon and therewith along the base, and carrying the reproducing tool; an attachment capable of converting vertical into inclined lines; an attachment for lengthening designs; an attachment for shortening designs; and an attachment for reproductions in three dimensions.

The invention also consists in the copying devices hereinafter described by way of example, with reference to the accompanying drawings in which:

Figures 1 and 1b are a plan view and a side elevation respectively of a device in which the vertical lines of a design are converted into inclined lines, Figure 1a showing one example of such conversion;

Figures 2 and 3 and 2b and 3b are plan views and side elevations respectively of the device showing it respectively applied to the shortening and lengthening of designs horizontally, Figures 2a and 3a being examples of such conversion; and

Figure 4 is an elevation of the device applied to three dimensional reproductions.

Referring to Figure 1, showing the invention applied to reproduction by inclined distortion, 1 is a base to which

2

the image or matrix to be reproduced is secured, which base may be a component of the device if the latter is constructed as a self-contained unit or be constituted by a machine table if the device is intended to be used as an auxiliary attachment. 2 is a first transverse carriage mounted on the base 1 in such a manner as to be capable of sliding along it. 3 is a second carriage carrying a stylus 3' by means of a bracket 3'', which second carriage is mounted on the carriage 2 and partakes of its movements along the base, and is capable of sliding transversely of the direction of movement of the first carriage 2. 4 is a top slide mounted on the stylus carrying second carriage 3 and partaking of the movements thereof, and adapted to slide thereon and therewith along the base 1 carrying the matrix, the said top slide carrying the reproducing tool of the copying machine, which tool is attached by means of a suitable adaptor at 17. 5 is an adjustable bar, pivoted on the first carriage 2 at 5' and adapted to be adjusted thereon in any desired inclination to act as a guide for the sliding movement of the top slide 4. A triangular member 4' is pivotally attached underneath the top slide 4 and carries three rollers 4'' between which the bar 5 is located to serve as a guide for the movement of the top slide 4.

This arrangement ensures that when the stylus 3' carried by the second carriage 3 is moved across the base, following a vertical line in the master design, the top slide 4 controlling the movement of the copying tool is caused by the inclined bar 5 to follow an inclined path, thereby causing the vertical line on the matrix to be reproduced as an inclined one. Figure 1a shows the reproduction of an inclined ellipse from a true circle.

For the purpose of effecting distortions by elongation or reduction in the horizontal direction, the adjusting bar 5 is disconnected and as shown in Figures 2 and 3, a lever 6 is pivotally connected through a top slide 8, hereinafter referred to, to a slide 7 and a slide 7a, which is integral with the slide 7 and arranged to slide up and down in an extension 1a of the base 1, the slides 7 and 7a being at right angles to each other. The slide 7 fitting between guides 7' serves as a guide to the carriage 3 by means of the guides 7' which are integral with the carriage 3 and the movement of the carriage 3 on the carriage 2 is accompanied by the movement of the said slides 7, 7a and 8 in the same direction. The lever 6 is also pivotally connected to the carriage 3 through the slides 9 and 10 which are hereinafter referred to, and which like the slide 8 are slideable on the lever. The lever 6, which may consist of two rods connected together at a suitable distance from one another by means of end-pieces 6', carries three slides, two of which are adapted to be adjusted in the longitudinal direction thereof relatively to the point of its connection to the said top slide 7. The first slide 8, serving as a pivot of the lever 6, is mounted towards one end thereof and is pivotally connected with the slides 7 and 7a; the second slide 9 is mounted between the said first slide 8, which acts as a pivot of the lever, and the slide 4 which carries the copying tool by means of a suitable adaptor 17 and the third slide 10 is mounted on the part of the lever near its opposite end. The adaptor 17 is secured to the slide 4 and the lever 6 pivots thereon through the member 17' attached to the lever. The second and third slides 9 and 10 are adapted to be alternatively connected to the tool supporting carriage 3 in such a manner as to follow all its movements whilst the connections are able to turn therein in a set position. For the purpose of lengthening, the slide 9 is set on the second carriage 3 whilst lever 6 is free to slide through it, the slide 10 being free to float. For the purpose of shortening, the slide 10 is set on the second carriage 3 whilst the lever 6 is free to slide through it, the slide 9 being free to float.

This arrangement enables the width of the design intended to be reproduced to be either shortened or length-

ened by connecting either the third or the second slide, 10 or 9, to the stylus supporting carriage 3, as shown in Figures 2a and 3a respectively.

The attachment just described may also be used for effecting the distortion of the design in the direction of height by simply securing the master image or matrix to the base 1 in a position displaced through an angle of 90°.

According to the present invention, the device may be modified to be suitable for three dimensional work, by causing the tool and the stylus of the machine to rise or drop when the master design is in relief. This arrangement is shown in Figure 4.

In this case a bracket 18 is attached to the stylus supporting carriage 3, in substitution for the bracket 3'', which bracket 18 is provided with a guide for a vertically moving slide 19, to which the stylus 20 following the master design is attached and which carries a horizontally moving slide 21 moving in guideways provided therein. The slide 21 is in vertical sliding engagement with a vertical guide 19' which is mounted in the adaptor 17 serving as a pivot for the lever 6. The slide 21 has attached to it a rod 22 carrying the reproducing tool (not shown), and fitted by means of a socket in the centre of the slide 21.

With such an arrangement, when the operator causes the stylus to follow a matrix in relief, the stylus is able freely to rise and fall according to the profile of the matrix, and the reproducing tool is compelled to follow such vertical movements. This movement of the reproducing tool in a third dimension is carried out by the attachment in addition to the movements in the other two dimensions as above described.

The details for carrying the invention into effect may be modified without departing from its scope.

What is claimed is:

1. A copying device capable of effecting controlled variations of geometrical forms and other shapes comprising: an elongated base to which the image or matrix to be reproduced is secured; a first carriage capable of sliding along the said base; guiding means on the base for the said first carriage; a stylus-carrying second carriage mounted on and capable of moving with the said first carriage along the base and being also capable of sliding at right angles to the said sliding along the base; guiding means on the first carriage for the sliding movement of the second carriage at right angles to the movement of the first carriage along said base; a top slide mounted on the second carriage and being capable of sliding thereon in the direction of movement of said first carriage and movable with said second carriage in its direction of movement; an adaptor carried by the said top slide for the reception of a reproducing tool; a disconnectable bar

pivoted to the first carriage in any desired inclination and means on the said top slide in guiding engagement with the bar, whereby during copying vertical lines of the image or matrix are converted into inclined lines.

- 5 2. A copying device as claimed in claim 1 in which the base has an extension at right angles to it, and the second carriage an extension disposed over the said extension of the base, the device further comprising two slides fixed at right angles to each other and slidably mounted respectively on the said extensions of the base and second carriage and capable of allowing the sliding movement of the second carriage both transversely to the base and along it; a lever disposed above the second carriage and pivoted to the said top slide carrying the adaptor; and three slides 10 carried by the lever, the first one of which is mounted near the top end of the lever and is pivotally connected with the said two slides fixed at right angles to each other and respectively mounted on the said extensions of the base and second carriage, the second one is mounted between 15 the said first slide and the pivotal connection with the top slide on the second carriage, and the third slide is mounted near the opposite end of the lever, the second and the third slides being adjustable in the longitudinal direction of the lever; and means for connecting the second or the third 20 slide to the lever and to the second carriage as required, the second carriage being provided with longitudinal slots for the passage of these connecting means, whereby the designs to be copied may be lengthened or shortened.
- 25 3. A copying device as claimed in claim 2 adapted to 30 effect controlled variations in three dimensions and including a first bracket attached to the second carriage, a second bracket carrying a stylus mounted on said first bracket for said second bracket, a slide mounted on the second bracket 35 for horizontal movement thereon, a vertical guide mounted on the top slide through said adaptor and along which the slide on the second bracket is vertically movable, the horizontal slide being adapted to receive the reproducing tool.
